UNITED STATES PATENT OFFICE

2,625,806

MERCANDISE DISPLAY CABINET

Garland C. Kennedy, Petersburg, Va., assignor of
one-half to Elbert L. Pugh and Julian A. Pugh,
doing business as Pugh's Super Market, Peters-
burg, Va.

Application March 29, 1950, Serial No. 152,706

1 Claim. (Cl. 62—89.5)

1

This invention relates to merchandizing and more particularly to a cabinet for displaying and preserving produce, particularly vegetables.

Heretofore, numerous devices of this nature have been proposed in which various means has been incorporated for preserving the produce, among these refrigeration and water sprays, but these prior art devices have presented numerous difficulties, such as lack of control for accommodating different types of vegetables and vegetables in various degrees of preservation.

It is, therefore, an object of this invention to provide a display cabinet in which there are provided troughs or bins for supporting the produce for sale, there being also provided means for subjecting the produce to an exceedingly fine atomized spray of refrigerated water.

It is a further object of the invention to provide a display cabinet for produce in which means is provided for regulating the cycle of operation of a water spraying system whereby the produce will be subjected to such spray for predetermined periods of time at predetermined intervals.

It is a further object of the invention to provide a display cabinet for produce in which adjacent portions of the produce may be subjected to a water spray of varying intensity.

It is a further object of the invention to provide a display cabinet for produce in which a refrigerated water spray system is incorporated, the refrigeration for this system being obtained from the normal refrigeration system incorporated in the cabinet and in which the spraying cycle may be either automatically or manually controlled.

It is a further object of the invention to provide a refrigerated water spray system for use with a display cabinet the refrigeration for this system being obtained from the normal refrigeration system incorporated in the cabinet.

Further objects and advantages of the present invention will be apparent from the following description taken in conjunction with the accompanying drawing, wherein:

Fig. 1 is a view in perspective of a display cabinet constructed in accordance with this invention and showing the internal arrangement whereby the water supply for the spray system is refrigerated;

Fig. 2, a schematic diagram of the water spray system showing an automatic timer for controlling the spraying cycle connected thereto; and

Fig. 3, a fragmentary detail view showing the manner of incorporating a manual timer or control for the spray system.

With continued reference to the drawing there

is shown in Fig. 1 a conventional produce display cabinet 10 having a lower closed body portion 11 provided with access doors 12 which permit access to a refrigerated storage compartment 13 located in the base 11 of the cabinet. This compartment is maintained at a relatively low temperature by refrigerated coils 14 disposed therein, the refrigerant for these coils being supplied by a conventional refrigeration apparatus not shown.

The cabinet 10 is provided with an upstanding back wall 15 and an overhanging shelf 16 which usually serves to conceal a light source for illuminating the storage bins or trays 17 formed by the upper surface of the base 10. Trays or bins 17 are separated by partitions 18 which normally may be disposed at any desired location in order to accommodate the particular quantity of any specific product to be displayed. The upstanding back wall 15 is provided with a front panel 19 which may comprise a mirror or which may serve to receive advertising material and this panel also serves to conceal refrigerating coils 20, relatively warm air being supplied to these coils 20 through louvres 21 adjacent the top of the back wall and beneath the shelf 16, the air cooled by coils 20 flowing outwardly through louvres 22 adjacent the rear of the trays or bins 17 to cool the produce disposed therein.

It has been found in practice that produce is maintained in a fresh and palatable condition for an appreciably greater time by providing a spray of refrigerated water which is projected over the top of the produce in the form of a relatively fine mist which settles thereon and which materially contributes to the appearance and condition of the produce. It has also been found that the quantity of water utilized and the duration of the spray period is directly affected by the type of produce and by the condition thereof and consequently in order to provide an apparatus which takes advantage of this situation, there is disposed adjacent each tray or bin 17 a spray nozzle or head 23 through which refrigerated water is projected in the form of a relatively fine atomized spray or mist.

As best shown in Fig. 2, the spray system comprises a manifold or header 24 to which is attached a plurality of pipes 25 each leading to a spray nozzle or head 23. Also incorporated in each pipe 25 adjacent the nozzle 23 is a valve 26 provided with a finger engaging lever 27 which permits convenient individual adjustment of the output of each nozzle 23.

The manifold or header 24 is connected by a

conduit 28 to a coil 29 disposed within the base 10 of the refrigerated cabinet which serves to control water flowing therethrough. The coil 29 is connected by a conduit 30 to a solenoid operated control valve 31 which in turn is connected through a strainer 32 to a main shut off valve 33 and a water supply conduit 34. The solenoid operated control valve 31 is connected by a suitable cable 35 to an automatic timer 36 which may be set by means of control knobs 37 to open the valve 31 at predetermined intervals and for a predetermined period of time, thus permitting water to flow from the supply conduit 34 through the cooling coil 29 and be expelled from the spray nozzles 23. At the completion of the spraying interval, the timer 36 closes the valve 31 and flow of water ceases. The timer 36 is connected by a suitable cable 38 with a conventional electrical outlet 39.

Where automatic operation of the spraying system is undesirable or unnecessary, a manual switch control, shown at 40 in Fig. 3, may be connected from the outlet 39 through cables 38 and 35 with the solenoid operated valve 31, manual operation of the control buttons 41 serving to control the operation of the valve 31 and the flow of water through the system.

It will thus be seen that by the above-described invention there has been provided a completely automatic means for depositing a fine mist or spray of water on produce displayed for sale in a refrigerated display cabinet and in which the spray for any particular type of produce may be conveniently regulated. It will also be seen that installation of such a device in a conventional display cabinet is relatively simple and takes advantage of the refrigerating features thereof to cool the water for the spray system.

It will be obvious to those skilled in the art that various changes may be made in this invention without departing either from the spirit or scope thereof and, therefore, this invention is not limited by that which is shown in the drawings or by that which is described in the specification, but only as indicated in the appended claim.

What is claimed is:

A merchandise display cabinet comprising a hollow base having a back wall and a sloping top wall for supporting produce thereon, the back wall of said base projecting beyond said top wall, a front panel positioned forwardly of said back wall and projecting upwardly from said top wall to provide a passage between said front panel and said back wall and communicating with said hollow base, said front panel having openings at the upper and lower edge portions thereof providing for the passage of air therethrough, cooling means located between said back wall and said front panel for cooling the warm air admitted through the openings at the upper edge portion of the front panel and discharging through the openings at the lower edge portion, additional cooling means positioned in said hollow base, a plurality of spray nozzles mounted on said base adjacent to said front panel and projecting forwardly thereof, a water coil disposed in said hollow base in heat exchange relation with said additional cooling means and connected to said spray nozzles, and means for supplying water to said water coil, whereby said additional cooling means pre-cools said water before its discharge through said spray nozzles and cools the top wall which supports the produce.
